(57) **CLAIM**

The ornamental design for a bottle, as shown and described.

DESCRIPTION

FIG. 1 is a perspective view of a bottle, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view similar to FIG. 1, but showing the band at the base of the closure rotated to the unlocked position; and,

FIG. 9 is a perspective view similar to FIG. 8, but showing the cap portion without broken lines therein.

The broken lines depict environmental structure that forms no part of the claimed design.
